UNITED STATES PATENT OFFICE.

BERTHOLD KLAFTEN, OF BERLIN-GRUNEWALD, GERMANY.

THERMOSTAT.

Application filed February 16, 1924. Serial No. 693,244.

This invention relates to a thermostat which is preferably designed for the automatic regulating of the draught for heating plants, especially hot-water or steam heating, for drying plants and everywhere where a regulating element is adjusted in dependence upon the heat. The thermostat has externally the usual appearance. According to international conventions connecting 10 pieces for boilers must generally possess 1 inch of gas-pipe thread, whereby the diameter for the protecting tube of the thermostat is determined which dips into the boiler. The length of the thermostat must be selected 15 comparatively great in order that the regulator shall be immersed for a sufficient depth into the water or steam, hot air or the like so that it reacts consequently to a determined average temperature. Thermostats, in which metallic or bi-metallic strips or elements are enclosed in a protecting tube, are known. In the thermostats of known type in which the element for regulating the draught is mechanically controlled 20 this is always effected in such a manner that the longitudinal expansion of the metallic or bi-metallic elements or rods is utilized for acting upon the draught regulating element. For the thermostat according to the 25 present invention, the outer dimensions of which are prescribed, no practical solution in this way is possible owing to the comparatively low temperatures in consideration, so that two bi-metallic rods are used which are 30 fixed at the lower ends so that the upper ends of the same are free as well to displace themselves in the longitudinal direction as to move towards one another or away the 35 one from the other.

The invention consists in that the several known means and arrangements are combined in such a manner that two bi-metallic strips are fixed with their lower ends on the bottom plate of a protecting tube and that the upper ends carry articulated members which are connected with one another after the manner of scissors and act mechanically upon an element of known type for adjusting the lever system of the draught registers.

An embodiment of the invention is illustrated by way of example in the accompanying drawing which shows a part sectional and a part elevational view.

1 is a protecting tube known per se which is closed at the lower end by means of a cap 2 adapted to be screwed therein. Two

thermostatic elements 3 are fixed in this cap 2 so that they form in the normal position an acute angle between themselves. On the upper ends of these elements 3 arms 5 are 60 pivoted at 4 which are connected with one another by a joint 6 after the manner of scissors blades. A sleeve 7 is screwed on the upper end of tube 1 and on this sleeve 7 another sleeve 8 is screwed in the top plate 65 of which a lifting pin 9 is guided. The lifting pin 9 has at its lower end a disk 10 which bears on the upper ends of arms 5. The lifting pin 9 projects from the upper end of the sleeve 8 and bears against a lever 70 75 11 which carries a slidable weight 12 on the one arm and to the other arm of which a chain 13 is attached which leads to the draught regulating element. The lever 11 is movably guided in a guide piece 14 which is pivotally connected by means of a pivot bolt 15 with an arm 16 the bent end of which is fixed on the upper end of sleeve 8 by a screw 17. Owing to the expansion and contraction of the thermostatic elements 3 the 80 ends of the arms 5, operating as scissors, are raised or lowered whereby, through the intermediary of the elements 9, 10, 11, 12, 13 and 14 the regulating element is operated. This operation is indicated by dash and dot lines 85 in the only figure of the drawing. In the form of construction shown by way of example the bi-metallic thermostatic elements are made from zinc and iron. The metals may however be chosen at will. 90

The bi-metallic rods 3 of the thermostat are arranged the one with regard to the other so that the metals possessing a low coefficient of expansion are situated on the inner side and the metals possessing the higher coefficient of expansion are situated on the outer side. In this arrangement the free ends of the rods will be moved towards one another owing to the expansion due to the increasing heat, but move away from one another at decreasing heat. To arrange the rods in such a manner that their free ends move away from one another at increasing heat and move towards one another at the cooling would fall within the range 95 of the present invention. 100

I claim:

1. A thermostat comprising a protecting tube; a sleeve secured to the top of said tube; a pair of thermostatic elements arranged in said tube; a pair of arms pivoted to each other intermediate their ends and 110

- one end of each arm being connected to the end of its respective thermostatic element; a disk slidably mounted in said sleeve and adapted to be operated by the other ends of said arms; and a lifting pin secured to said disk and slidably mounted in said sleeve for transmitting the action of the thermostatic elements by means of said arms.
2. A thermostat comprising a protecting tube; a sleeve secured to the top of said tube; a pair of thermostatic elements arranged in said tube; a pair of arms pivoted to each other intermediate their ends and one end of each arm being connected to the end of its respective thermostatic element; a disk slidably mounted in said sleeve and adapted to be operated by the other ends of said arms; and means for transmitting the action of the disk to a draft register control.
3. A thermostat for a draft register control comprising a pair of thermostatic elements; a pair of arms pivoted to each other intermediate their ends and one end of each arm being connected to the end of its respective thermostatic element; and means for transmitting the movement of the other ends of said arms, in accordance with the action of said elements, to the draft register control.
4. A thermostat for a draft register control comprising a pair of thermostatic elements; a protecting tube enclosing said elements; a pair of arms pivoted to each other intermediate their ends and one end of each arm being connected to the end of its respective thermostatic element; and means for transmitting the movement of the other ends of said arms, in accordance with the action of said elements, to the draft register control.
5. A thermostat for a draft register control comprising a pair of thermostatic ele-
- ments; a protecting tube enclosing said elements; a pair of arms pivoted to each other intermediate their ends and one end of each arm being connected to the end of its respective thermostatic element; and a disk and lifting pin associated with the other ends of said arms for transmitting the movement of the thermostatic elements to the draft register control.
6. A thermostat for a draft register control comprising a protecting tube; a cap secured at one end on said tube; a pair of thermostatic elements in said tube having one end of each element projecting into said cap; a sleeve secured to the other end of said tube; a pair of arms pivoted to each other intermediate their ends and one end of each arm being connected at the other end of its respective thermostatic element; and means in said sleeve for transmitting the movement of the other ends of said arms, in accordance with the action of said elements, to the draft register control.
7. A thermostat for a draft register control comprising a protecting tube; a cap secured at one end on said tube; a pair of thermostatic elements in said tube having one end of each element projecting into said cap; a sleeve secured to the other end of said tube; a pair of arms pivoted to each other intermediate their ends and one end of each arm being connected at the other end of its respective thermostatic element; and a disk and lifting pin in said sleeve for transmitting the movement of the other ends of said arms, in accordance with the action of said elements, to the draft register control.

In testimony whereof I affix my signature.

BERTHOLD KLAFTEN.
